UNITED STATES PATENT OFFICE.

MARSENA R. JULIAN, OF BIRMINGHAM, ALABAMA.

BLOCK-SIGNAL SYSTEM.

1,243,418.

Specification of Letters Patent. Patented Oct. 16, 1917.

Application filed July 31, 1914. Serial No. 854,392.

To all whom it may concern:

Be it known that I, MARSENA R. JULIAN, citizen of the United States, residing at Birmingham, in the county of Jefferson and State of Alabama, have invented certain new and useful Improvements in Block-Signal Systems, of which the following is a specification.

My invention relates to block signal systems, and particularly to a block controlled cab signal system. With the ordinary block signal systems at present in use on practically all roads there is no way to prevent an engineer from running his train past any signal which may be set against it and no way to positively compel the engineer to reduce speed upon receiving either a cautionary signal or a danger signal. Sometimes the engineer runs his train past a signal set against him out of sheer carelessness or the desire to make up time, and on other occasions he passes the signal because he is unable to see it, as in case of heavy snow, or fog.

It has been proposed to display the proper signals within the cab of a locomotive so that the engineer cannot possibly fail to see the signals, but here again discretion is left with the engineer to run his train by the signals or to pay no attention to them if he so desires. This has led to many accidents and is a constant source of danger. Even where the engineer obeys the signals there is still another element of danger in the engineer maintaining too high train speed either along a normally perfectly safe portion of the track or in some particular section in his desire to make up for lost time, and as far as I know, no means has so far been provided which will automatically limit the maximum speed of the train or automatically bring the train either to a moderate speed in case of a cautionary signal being set against the train or bring the train to a stop in case a danger signal is set against the train.

The primary object of my invention is to provide means for automatically controlling the speed of trains in a block signal system and in this connection to provide means whereby in the first place the train cannot be run above a predetermined speed, even with a clear track; whereby in the second place when the engineer receives a cautionary signal due to the presence of a train

within a predetermined number of blocks ahead the speed of the following train shall be automatically cut down to a predetermined degree, and whereby in the third place when the train receives a danger signal due to the presence of a train a dangerous distance ahead the speed shall be automatically cut down to a minimum.

Another object of my invention is to so construct the mechanism that the automatic service application of the brakes shall not in any way interfere with the regular or usual application of the brakes by the engineer.

Another object of the invention is to provide a train controlled cab signal mechanism wherein on entering a block a "test" is made to show that the track wiring and wiring of the cab signal mechanism are in proper working condition and so formed that if they are not in proper working condition an application of the brakes shall immediately be made.

Still another object is to so construct my improved train control and signal mechanism that on entering a block a "danger" application of the brakes shall be made unless a clear signal or a cautionary signal is immediately received.

Another object is to so construct the signal mechanism that in addition to automatically controlling the speed of the train, signals shall be displayed within the cab of the engineer whereby he may readily determine whether he is running his train on a clear signal, a cautionary signal or a danger signal and further provide for the application of the brakes and a characteristic signal if by any chance the signaling mechanism is out of order and does not properly work.

Still another object is to so construct the mechanism that a break of any wire of the cab signal system, except the clear signal wire, will cause the brakes to be applied and, in this connection, to provide a mechanism wherein after the clear signaling wire breaks, while the brakes will not be immediately applied, yet, the brakes will be applied at the entrance end of each block and the danger signal will be displayed.

A further object in this connection is to provide means whereby after the clear signal wire breaks and the brakes are applied and the danger signal displayed, the engi-

neer may release the brakes and permit the train to go forward but not beyond a very low speed.

Still another object is to provide a cab signal mechanism in which there shall be at least two elements which must fail in order to permit a train to enter a block already occupied by a train.

Another object is to so construct the cab signal mechanism that if the wires leading from the "test," caution or danger contacts or shoes should break, the clear signal light shall immediately go out and the brakes be immediately applied and remain applied until the break or interruption in the broken wire is mended or until the engineer can cut out the signal mechanism, and in this connection to provide means whereby if the wire leading from the clear signal shoe or contact should be grounded the brakes will be applied.

Still another object is to provide a closed circuit cab signaling system in which a break or ground will cause a danger application of the brakes and thus compel the engineer to run his train at a very slow speed through the block until the next block is reached, and to provide means for cutting out the automatic mechanism if it becomes damaged.

Still another object in connection with the above is to provide for a display of a danger signal if the apparatus fails to work so that even if the train is running slowly the engineer will be informed of the break.

A further object is to provide means whereby a signal of some kind whether clear, cautionary, or danger, will always be received at the entrance end of each block and the failure to receive a proper signal will automatically give a danger signal and cause a danger application of the brakes.

Still another object is to provide mechanism whereby if the engineer is running his train slowly and gets a danger signal the brakes will be immediately automatically applied but whereby the engineer can immediately throw off the brakes provided the speed of his train is within the limit set for danger, this mechanism acting, however, if the speed is too high, to prevent the release of the brakes, and to this end to provide two circuit closers necessary to be closed in order to permit the release of the brakes, one circuit closer acting automatically and being dependent upon the speed of the train and the other being manually actuatable.

Still another object is to provide means whereby if a danger signal is received on entering a block, the train will be brought to a sudden stop unless the engineer closes the circuit, and whereby this closing of a circuit will release the brakes but will not permit the speed to be increased beyond five

miles an hour or some other predetermined rate, and whereby, if on entering a second block the train shall receive a danger signal, the train will be again brought to a full stop unless the engineer immediately closes said circuit.

Still another object is to provide a mechanism wherein, if a cautionary signal is received and if the train is running at a cautionary speed, that is, within a certain limit of speed, the cautionary signal will show, and brakes will be applied if the engineer does not close a certain circuit, but, wherein, if the engineer closes this circuit when the train is running at cautionary speed the brakes shall not be applied. If, however, the speed of the train is above what may be termed "cautionary" speed, then the brakes are not released until the speed of the train is reduced to a safe and predetermined degree.

Still another object of my invention is to provide a speed controlling means which is adjustable so that the speed of a train along a clear track cannot, without adjustment of the mechanism, be increased beyond a certain rate, and wherein the speed cannot be increased beyond a predetermined extent if for any reason it is necessary to run at a moderate speed or half speed along a certain stretch of track, and wherein again, the speed may be kept below a certain predetermined limit either along a certain stretch of track or in case the train receives a danger signal.

Still another object is to provide a speedometer which will show the engineer the speed at which his train is running, and to provide in connection with the speedometer, train controlling mechanism governed by the action of the speedometer.

Still another object in this connection is to provide a speedometer having thereon contact strips or members over which the pointer of the speedometer moves, the length of these contact members being adjustable and the train controlling mechanism being such that when the needle of the speedometer moves beyond a certain strip due to increased speed, the brakes will be immediately applied until the speed is reduced to the proper degree.

Other objects will appear in the course of the following description.

My invention is illustrated in the accompanying drawings, wherein:

Figure 1 is a diagrammatic view of a cab signal system constructed in accordance with my invention, the view showing the cab wiring.

Fig. 2 is a diagrammatic view of the track wiring.

Fig. 3 is a longitudinal sectional view of one of the track contact switches.

Fig. 4 is a transverse sectional view of one

of the track contact switches, on the line 4-4 of Fig. 3.

Fig. 5 is a face view of the speed controlling speedometer.

Fig. 6 is a perspective detail view of the connection between the contact member 107 of the speedometer and the arbor thereof.

Corresponding and like parts are referred to in the following description and indicated in all the views of the accompanying drawings by the same reference characters.

Referring to these figures X designates a railway car, locomotive or tender and mounted thereon preferably two on each side, and preferably so situated as to be disposed on the outside of the track rails are the shoes A, B, C and D. These shoes are each about eight feet long and four inches wide and are adapted to engage with certain track contact switches of the kind shown in my prior application for patent, Serial No. 759,817, filed April 8, 1913. These track contact switches and their connection will be later described, but generally speaking, it may be said that the track contact switches when engaged by a shoe are thrown over so as to make engagement with an electrical conductor so that if this conductor has been grounded by the presence of a train in a block ahead the cab signal circuit connected to the particular shoe engaging the track contact switch will be grounded, thus permitting current to pass through the cab signal circuit in question and cause the actuation of the signal and speed controlling mechanisms, now to be described.

Disposed within the engine cab is a speedometer Y. By the term speedometer I intend to include any mechanism, an element of which is shiftable in one direction upon an increase of the speed of a train and in another direction upon a decrease of the speed, whether this element actually measures and indicates the speed or not.

In connection with my controlling mechanism I employ a pipe Z which forms a portion of an air brake air line, and is preferably a pipe leading from the equalizing reservoir of an air brake system, this pipe having a vent controlled by a valve therein whereby pressure may be reduced. The valve is designated z. When this valve is open the air within the equalizing reservoir will be vented and thus a reduction in pressure be made in the train pipe which will cause an application of the brakes. When the valve is closed, of course, there is no effect upon the air brake system.

Mounted upon the engine or operated thereby is a generator G of any ordinary or usual type, or if preferred a storage battery.

The shoe A will hereafter be termed the "test" shoe, as it is through this shoe that a test is made upon entering a block to see that all the parts are working properly, and

that none of the wires of the various circuits are disconnected or broken. The shoe B will hereafter be termed the "cautionary" shoe, as it is through this shoe that cautionary signals are received indicating the presence of a train within such a distance ahead as to require that the following train shall be run with caution. The shoe C is hereafter designated the clear shoe as a signal received through this shoe shows that the track ahead is entirely clear, at least for a certain number of blocks. The shoe D is hereafter termed the "danger" shoe as it is through this shoe that the danger signals are received, indicating that there is a train on the block ahead and that the speed of the following train must be cut down to a minimum.

Referring now particularly to Fig. 1 it will be seen that from the danger shoe D extends a conductor 2 which connects at o with a feed-wire 3 leading from the generator. From the cautionary shoe B extends a conductor 4 leading to feed wire 3 and also intersecting it at o. From the test shoe A leads a conductor 5 which at p connects with the feed wire 6. From the clear shoe C extends a conductor 7 which connects with the feed wire 6 at p. It will thus be seen that I provide four circuits connecting each shoe with the generator and that when any shoe is grounded by engagement with the track contact switch or with any other suitable track contact, current will pass from the generator to the shoe and back by the ground to the generator.

Disposed in the conductor 2 is a relay magnet 8 controlling two points 8^a and 8^b. Inasmuch as two-point relay magnets are commonly used in block signal systems it is not believed necessary to describe this construction in detail. Disposed in the conductor 4 is a relay magnet 9 having the points 9^a and 9^b controlled thereby. Disposed in the conductor 5 is a relay magnet 11 controlling points 11^a and 11^b. Also disposed in the conductor 4 is a relay magnet 10 controlling points 10^a, 10^b and 10^c. Disposed in the circuit formed by the conductor 7 is a relay magnet 12 controlling points 12^a, 12^b and 12^c.

Extending from the shoe B is a conductor 13 which is grounded at 14 and extending from the shoe D is a conductor 15 grounded at 16. Disposed in the conductor 13 is a relay magnet 17 and in the conductor 15 is a relay magnet 18.

From the conductor 5 extends a wire 19 which passes through a relay magnet 20 controlling points 20^a and 20^b and 20^c. From the magnet 20 this wire passes to a contact 21 coacting with a key 22 connected to a ground. From the conductor 2 extends a wire 23 leading through a relay magnet 24 to a conductor 25 coacting with

the grounded key 26. The keys 22 and 26 are normally in position to break the circuits to the grounds connected thereto, but may be manually pushed into engagement 5 with their respective contacts. These magnets 20 and 24 when deenergized may be energized by the actuating keys 22 and 26. It will be obvious also that both of these magnets are "stick" relays, or retaining relays. Both of these relays are normally energized by current flowing through them as follows:

The current flows from the wire 2 by the wire 23 through the magnet 24 and by the 15 wire 27 to the point 24^a thence by the wire 28 to the point 8^a thence by the wire 29 to the ground 30. Current flows through the magnet 20 from the conductors 5 and 6, through the conductor 19, through the 20 magnet 20 by the conductor 31 to the wire 32, thence to the point 20^a and thence by the wire 33 and the point 9^a to the ground 30.

The mechanism for operating the brake 25 comprises an armature 34 controlled by a magnet 35. This armature 34 when the magnet 35 is energized is drawn upward against the force of a spring and is operatively connected to a vent valve 2 which is disposed to vent the equalizing reservoir of an air brake system. When the armature is drawn against the magnet 35 the valve is held closed. When the magnet 35 is deenergized, however, the spring will pull the armature away from the magnet thus opening the valve and reducing the pressure in the equalizing reservoir, thus applying the brakes in a manner well-known to those conversant with the art.

40 The speed controlled magnet 37 controls a point 37^a which is connected to the magnet 35 by the wire 36. The point 37^a is normally in electrical engagement with one terminal of a wire 38 the other terminal of 45 which is in electrical engagement with the point 20^a. This point 20^a is connected by a wire 39 to a point 24^c which is normally in electrical engagement with the wire 40 leading to the conductor 2. Thus current is 50 normally passed through and energizes the magnet 35. The speed controlled magnet 37 which controls the point 37^a is disposed in a conductor 41 which at one end is connected to a ground 42 and which at the 55 other end is connected to the pointer or other moving part of a speedometer or governing mechanism designated generally Y. This pointer is designated 43 and moves over a plurality of contact strips 44, 45 and 60 46. The contact strip 44 governs the speed of the train when a clear signal has been received, the contact strip 45 governs the speed of the train when a cautionary signal has been received, and the contact strip 46

governs the speed of the train when a danger signal has been received.

From the contact strip 44 extends a wire 47 which is normally in contact with the point 48^c of a retaining relay magnet 48. This point 48^c is electrically connected to 70 a wire 49 the terminal of which is normally in engagement with the point 10^c of the relay 10 and this point 10^c is connected to the wire 50. When the point 10^c moves out of engagement with the wire 49 it moves into 75 engagement with the wire 53 which is electrically connected to the strip 46. The contact strip 45 is connected to the wire 54 one terminal of which is opposed to and spaced from the terminal of the wire 47, this terminal being normally out of contact with the point 48^c but engaged by the point 48^c when the point 48^c moves away from the terminal of the wire 47.

The relay 48 is a "stick" relay, that is a 85 retaining relay and is normally energized by current passing from the conductor 6 through the magnet 48 to the conductor 55, thence by the conductor 56 to the point 48^a, thence by the wire 57 to the point 20^b, thence 90 by the conductor 58 to a point 11^b and to a ground 58^a connected thereto. The relay magnet 10 is a stick relay and current normally passes through it from the conductor 3 through the wire 59 to the point 95 10^a, thence by the wire 60 to the point 24^b, thence by the wires 61 and 58 to the point 11^b and the ground 58^a.

The point 48^c constitutes the means for making or breaking a circuit through the 100 contact strips 44 and 45. The point 10^c controls the cutting out of the point 48^c entirely in one position and the completion of the circuit through the strip 46. The point 48^b controls the passage of current to either 105 the clear signal or the cautionary signal and the point 10^b either completes the circuit through the point 48^b and thence completes the circuit through the clear signal lamp or breaks the circuit through 48^b and completes the circuit through the danger signal lamp.

The clear signal lamp is designated 62 and is connected on one side to the ground 63. The wire 64 leads from the clear signal 115 lamp, the terminal of this wire being disposed to be normally engaged by the point 48^b. The cautionary lamp is designated 66 and from it leads a wire 67 the terminal of which is opposed to the terminal of the wire 120 64 and is adapted to be engaged by the point 48^b when this point is dropped by the de-energizing of the magnet 48. The danger lamp is designated 68. This like the cautionary and clear lamps is connected on one 125 side to the common ground 63 and on the other by a wire 69 the terminal of which is opposed to the terminal of the wire 65 and

is adapted to be engaged by the point 10^b when the point is dropped by the deenergizing of the magnet 10.

The relay 11 it will be noted is a "stick" relay, or retaining relay, and extending from the wire 5 is a wire 70 co-acting with the point 11^a, this point being connected by a conductor 71 to the point 9^b, normally in engagement with the terminal of the wire 10^b which extends to the point 12^b with which it is normally in engagement. From the point 12^b extends a wire 73 to the point 8^b and thence to the ground 74. While the relay 11 is in a normally closed circuit, the 15 resistance of the relay 37 and light 62, also in this circuit, cuts down the flow of current to such an extent that the relay 11 will only be energized to attract its points when the test shoe is grounded to shunt the relay 37 20 and light 62.

The point 11^b controls the deenergizing of the "stick" relays 10 and 48. The point 11^a makes a stick relay of the magnet 11. The point 9^b controls the deenergizing of the 25 magnet 11. The point 9^a controls the deenergizing of the magnet 20. The point 12^a controls the return circuit from the test shoe A and controls the energizing or deenergizing of the several lamps 62, 66 and 68 and 30 also controls the energizing or deenergizing of the speed controlling magnets 37. The point 12^b controls the passage of current through the magnet 11 in the same manner as the point 9^b and also controls the energizing 35 of the magnet 10. The point 12^a controls the energizing of the "stick" relay magnet 48. Leaving out of consideration the magnets 17 and 18 and the wires 13 and 15 the operation of which will be later stated 40 and considering the points 17^a and 18^a as ordinary conductors, the operation of the invention is as follows:—

When the test shoe is grounded by electrical engagement with a track contact member current flows from the generator by the wire 5 to shoe A energizing the stick relay magnet 11. This breaks the circuit through the wire 58 and thus breaks the circuit to the common ground for both of the relay 50 magnets 10 and 48. The deenergizing of the relays 10 and 48 breaks the circuit through the white light and speedometer circuits. The breaking of the circuit through the speedometer circuits causes the deenergizing 55 of the magnet 37 and applies the brakes. When the shoe A leaves the track contact member the conductor 5 remains grounded at the ground 74 through the "stick" relay point 11^a and hence the brakes 60 continue applied and the signal lamps remain inactive until some kind of a signal whether clear, cautionary or danger is received. It is to be understood at this point that this "test" is made immediately upon

the entrance of a train into a block. The object of the "test" is to put on the air brake at the entrance of a block and hold the brakes applied unless a clear signal is received.

Almost immediately after the shoe A has engaged with the corresponding track contact the shoe C engages with the corresponding track contact and thus, if the track ahead is clear the shoe C will be grounded. When the shoe C is grounded current passes from the generator to the shoe C energizing the magnet 12. This through the point 12^b breaks the circuit between the ground 74 and the relay magnet 11, allowing the point 11^a to open and 11^b to close and places a ground back upon the stick relay magnets 10 and 48 which were previously deenergized by the "test". The magnet 10 is energized by current passing from the generator over the wire 3, through the magnet 10 to the point 12^b of the relay 12, and from this point through the wire 73 and point 8^b of the relay 8 to the ground 74. The magnet 48 is energized by current from the generator over the wire 3 and wire 6 to the magnet 48 and through the wire 55 to the relay point 12^a of the relay 12 and through the wire 73 to the relay point 8^a of the relay 8 and so to the ground. The movement of 90 12^a and 12^b thus completes a circuit through the magnets 10 and 48 which is rendered permanent by the grounding of the points 10^a and 48^a. The point 10^a is grounded by current passing from the magnet 10 through the wire 59, relay point 10^b, the wire 60, 100 the relay point 24^b, the wire 61 and the wire 58 to the relay point 11^b and so to the ground 58^a, while the relay point 48^a is grounded by current from the magnet 48 through the wire 55, the relay point 48^b, the wire 57, the relay point 20^b, the wire 58 and the relay point 11^b to the ground 58^a. The energizing of the magnets 10 and 48 closes the circuit once more through the clear signal 110 62 and the clear signal contact strip 44, reclosing the air valve, the circuits being held closed until the next block is reached. The magnet 12, however, is deenergized when the shoe leaves the contact. Thus, after a clear signal has been received the 115 air valve which has previously been opened by the "test" is closed, the clear signal lighted and rendered active and this clear signal light remains active through the block or until the next signal is received.

If, after the test, a cautionary signal is received by the cautionary shoe B being grounded by engagement with a cautionary track contact, then the magnets 9 and 10 will be energized (the magnet 10 having 125 been previously deenergized by the test). The energizing of the magnet 9 breaks the ground 74 of the "stick" relay 11 and closes

a circuit to the points 10^a and 48^b. It also breaks the circuit between the ground 30 and the magnet 20, allowing the points 20^a, 20^b and 20^c to open. The opening of the 5 point 20^c cuts off the current to the brake magnet 35 allowing the brakes to be applied. The energizing of the magnet 10 causes the point 10^a to close establishing a circuit through the magnet 10 to a common 10 ground through 11^b. This permits current to flow to 48^b and 48^c. The magnet 48 has been deenergized by the test and therefore, current flows from 48^b through the wire 67 to the green light and from 48^c through the 15 wire 54 to the strip 45. If the train is running at a proper speed, that is, running under a cautionary signal the pointer 43 will be in contact with the strip 45 and hence the current will flow to the magnet 37 as 20 previously stated. If, however, the train is running at a speed greater than the proper speed, as for instance a speed greater than twenty miles an hour, the pointer 43 will be 25 beyond the end of the strip 45 and hence, the circuit will be broken not only at the point 20^c but also at the point 37^a.

The grounding of the danger shoe D by engagement with a track contact energizes the magnet 8. This breaks the circuit between the ground 74 and the relay magnet 11, allowing the point 11^a to open and closing the circuit through 11^b to the ground 58^a. This grounds both points 10^a and 48^a through the point 11^b, but does not ground 30 the magnets 10 and 48 which remain deenergized as left by the test signal. The energizing of the magnet 8 breaks connection from the ground 30 through the magnet 24. This breaks the circuit through 24^b through 35 the "stick" relay 10, if it has not previously been broken by the test. The deenergizing of the magnet 24 breaks the circuit through the magnet 35, thus applying the brakes. Thus when a clear signal is received the strip 40 44 is active and the strips 45 and 46 are inactive. When a cautionary signal is received the strips 44 and 46 are inactive and the strip 45 is active, while when a danger signal is received the strips 44 and 45 are 45 rendered inactive, their circuits being broken at 48^a and 10^a, respectively, and the strip 46 is rendered active, its circuit being closed at 10^a. As previously stated, the pointer 43 is 50 connected by means of the wire 41 to the magnet 37. If the strip 44 is active, the magnet 37 will be energized just so long as the arm 43 is in contact with the strip 44. When, however, the pointed 43 moves out of 55 electrical engagement with the contact 44 as 60 by the speed of the train rising beyond a predetermined point, which is controlled by the length of the strip 44, then this circuit will be broken. The magnet 37 will be deenergized and will cause a breaking of the circuit 65 between the wire 2 and the magnets 35,

the armature 34 will be released and the brakes will be applied. This will slow down the speed of the train and when once more the pointer 43 comes into electrical engagement with the strip 44 the circuit 70 through the magnet 37 will again be completed which will close the point 37^a to again complete the circuit from the wire 2 through magnets 35. This will cause the armature 34 to close, again shifting the valve to a 75 closed position and releasing the brakes.

If, now, the strip 44 is rendered inactive by reason of the train having received a cautionary signal through the cautionary shoe, the circuit is completed through the 80 magnet 37 and no application of the brakes is made as long as the pointer 43 is in contact with the strip 45. If, however, the speed of the train increases so as to shift the pointer beyond the strip 45; that is, if the 85 speed of the train increases beyond a proper speed for a train running under a cautionary signal, then the circuit through the magnet 37 will be broken and the brakes will be applied until the train has slowed down to 90 such an extent that the pointer 43 will again come into electrical engagement with the strip 45. When this has occurred the circuit through the magnet 37 will be again completed and the circuit through the magnets 35 again established, causing the release of the brakes.

If now, on the other hand, the strips 44 and 45 are both inactive and the strip 46 is active, that is, is connected to the generator, 100 then so long as the speed of the train is below the minimum permitted when the train is running under a danger signal, as for instance five miles an hour, the circuit will be completed through magnet 37 and no application of the brakes will be made. If, however, the train's speed exceeds the danger limit the circuit will be broken through the magnet 37 and the point 37^a will shift to 105 break the circuit through the magnets 35 110 and the brakes will be applied until the train decreases its speed to the danger limit, whatever that may be.

It will thus be seen that when running on a clear signal the brakes will not be applied 115 unless the speed exceeds the speed which is deemed safe for any particular stretch of track. When, however, the train has received a cautionary signal the brakes will be applied unless the train is running at a relatively slow speed, as for instance, 20 or 25 miles an hour. Where the train receives a danger signal, however, whether it has previously been running on a cautionary signal or under a clear signal, the brakes will 120 be applied and the train can be run only at or below the minimum rate of speed, five miles an hour.

When a cautionary signal has been received, which would, as previously ex- 130

plained, apply the brakes by deenergizing the magnet 20, the circuit through this magnet may be again completed by pressing the key 22, and provided the train is running at a speed less than the cautionary speed a circuit through the magnet 35 will be completed although, if the speed is greater than cautionary speed, this circuit will be open at the relay 37. If the train is running at a greater speed than cautionary at the time the signal has been received the circuit will be broken not only at 20° but also at 37°, and hence the circuit through the magnet 35 cannot be completed by pressing the button 22 until the train has had its speed reduced to the cautionary speed limit.

The same statement is equally true of the action when a danger signal is received. If when a danger signal is received the train is running at a speed within the danger limit, as for instance, less than five miles an hour, or any other predetermined speed, then when the circuit through the magnet 24 is broken by the energizing of the magnet 8, the circuit may be reinstated through the magnet 24, by pressing the button 26 which will once more reinstate a circuit through the magnet 35 and release the brakes. If, however, the speed, when the danger signal is received, is greater than five miles an hour, for instance, the pointer 43 will be beyond the strip 46, and, as a consequence, the circuit through the magnets 35 will be broken in two places; viz., at 24° and 37°; hence the train must slow down to a speed within the danger limit so as to close the circuit at 37° before the engineer may release the brakes by pressing the button 26.

The object of the conductors 13 and 15 is to keep a weak current flowing through the magnets 17 and 18 to the grounds 14 and 16 at all times so as to cut current off from the lights and speed controlling magnet 37 if either the danger or cautionary circuit wire should break. After this operation the circuit through the magnets 17 and 18 is broken and thus the circuit leading to the magnets 48 and 10 is broken, which breaks the circuit to the speed controlling magnet 37 and the lights.

In Fig. 2 I show a diagram of the track wiring and in Figs. 3 and 4 I show views of the track contact switches which I prefer to use in connection with my cab signal mechanism. In Fig. 3, 76 designates a casing supported on the ties 77. Disposed within the casing is a rock-shaft 78, as shown clearly in Fig. 4, having an upwardly extending arm 79 which is disposed in the path of the corresponding shoe on the truck. The rock-shaft 78 has projected from it a contact member 80 which when the rock-shaft is rotated in the direction of the arrow, Fig. 3, is adapted to engage with a contact member 81 from which a wire extends to the

proper relay of the track wiring system. The rock-shaft 78 also carries a radially projecting arm 82 to which is connected a spring 83. This spring, therefore, acts to hold the arm 79 in a vertical position. It is to be understood that the arm 79 may be rocked either in a direction reverse to the arrow in Fig. 3 or in the direction of the arrow. Of course, the oscillation of the arm 79 in the direction reverse to the arrow will not electrically connect the arm with the contact 81. The purpose of having the arm so arranged that it may be shifted in either direction is, of course, to permit the train to back, without closing the electrical connections through the block. There are four of these contact switches, designated respectively, *a*, *b*, *c* and *d* to correspond with the contact shoes *A*, *B*, *C* and *D*. The track wiring is practically the same as that used for three position semaphore signals. One block *F* is shown in Fig. 2 with the exit end of a block *E* and the entrance end of a block *G*. The rails of each block are operatively connected to a battery 84 and disposed within the block is a magnet 85 connected by a wire 86 to both rails. This magnet is to be energized when no train is on the block but deenergized by the presence of a train on the block. Controlled by the magnet 85 is a point 85^a which is normally in contact with the terminal of a wire 87. The point 85^a is connected by means of a wire 90 to a one-point relay magnet 91 and thence by wire 92 to the line wire 89. Hence, so long as the magnet 85 is energized, the magnet 91 will be energized. The magnet 91 controls a point 91^a which at its butt end is connected by wire 93 to the rails of the track of block *E*, for instance. This point 91^a coacts with the opposed terminals 94 and 95, being normally in contact with the terminal 94. The terminal 95 is connected by a wire 96 to the track contact switch *d*. The terminal 94 is connected by a wire 97 to a point 98^a controlled by a relay magnet 98. The relay magnet 98 is connected on one side to the line wire 89 and on the other side by a wire 99 to the point 100 at the entrance end of the block *G* which is controlled by a relay magnet 101, this magnet like the magnet 85 being connected with the track rails of the block *G*. The point 100 at its butt end is connected through a battery 102 with the line wire 89. The point 98^a is normally in contact with the terminal of a wire 103 which is connected to the clear contact switch *c* but when the point 98^a drops by the deenergizing of the magnet 98 it electrically engages with the terminal of a wire 104 which is connected with the cautionary contact *b*.

It will be obvious now that when a train arrives at the exit end of the block *E*, if there is a train upon the block *G*, the magnet 101 will be deenergized, causing the 130

point 100 to drop, breaking the circuit through the magnet 98 and causing the point 98^a to drop. This will break the circuit through the clear contact switch and 5 complete the circuit through the cautionary contact switch *b* thus giving a cautionary signal to the train. If, on the other hand, a train is in the block F when the train arrives at the end of the block E, the magnets 10 85 will be deenergized causing dropping of the point 85^a which will, thereby break the circuit through the magnet 91. This will cause the dropping of the point 91^a which will open the circuit through the clear contact switch and close the circuit through the danger contact switch. If no train is 15 on the track it is obvious that the magnets 91 and 98 will both be energized holding the contact points 91^a and 98^a in such position 20 as to connect the contact switch *b* with one of the rails, that is, to ground.

I of course do not wish to be limited to the track contact system, as above described, as it is obvious that this may be varied in 25 many ways and Fig. 2 is merely given for the purpose of showing one method of causing the grounding of the track contact switches by the absence or presence of trains on the block.

30 In Fig. 5 I show an enlarged face view of a speedometer, such as is illustrated diagrammatically at Y in Fig. 1. It will be seen that the dial 105 of this speedometer is cut away as at 106 and that the arbor upon 35 which the pointer of the speedometer is mounted extends through an insulator block and has mounted upon it a pointer or contact member 107 which moves over the contact strips 44, 45 and 46. These contact 40 strips are seated in arcuate slots and are adjustable along these slots and held from movement after being adjusted by the set screws 108, for the purpose of adjusting the strips 44, 45 and 46 so as to increase or decrease 45 the maximum speeds of the train allowed by the several strips. Thus it will be obvious that if the strips 44, 45 and 46 are moved in a counter-clockwise direction in Fig. 5 the pointer 107 will pass or escape 50 from these strips sooner, that is, at a lower train speed, than if the strips are shifted in a clock-wise direction. Thus, the maximum speed at which the train may run under a clear signal may be adjusted to any extent 55 required. The maximum speed at which the train may run under a cautionary signal may also be adjusted and the maximum speed under which the train may run under a danger signal may be adjusted. The adjustment 60 of these contact strips is to be made by some one in authority, and they are not intended to be shifted at the engineer's pleasure. If the maximum speed of the train under any circumstances, with a clear 65 track, is to be sixty miles an hour and the

engineer is not allowed to run his train beyond this limit, the contact strip 44 will be set to sixty miles and, thereafter cannot be changed by the engineer; thus at no time can the engineer run his train over sixty 70 miles and hour with a clear track or in like manner over the speed to which the strips 45 and 46 are set, if his train is running under a cautionary signal or under a danger signal.

75 By reference to Fig. 6 it will be seen that the arm or pointer 107 is intended to have a certain amount of play with relation to the arbor or shaft 108 of the speedometer. To this end the finger or pointer 107 loosely 80 surrounds the arbor 108 and is provided with a downwardly extending bifurcated lug 109 which engages over a pin 110 mounted on the member 111 attached to the shaft 108. With this construction the shaft 85 108 may have a certain play with regard to the finger 107, depending in amount upon the relative diameter of the pin and the width of the slot in the lug 109. The purpose of this is to prevent vibration of the 90 pointer 107, causing rapid intermittent de-energizing of magnet 37 when the pointer is at the end of one of the contact strips and further, to cause a full application of the 95 brakes if the pointer passes beyond the end of the active contact strip and then immediately returns. The arbor or shaft 108 will have to rotate a relatively large angular distance before the pointer will be drawn back into engagement with the contact strip. In 100 other words, if the maximum speed is set at fifty miles an hour and the train should run slightly above fifty miles an hour, the speed will have to be reduced to forty-five miles 105 an hour before the pointer or finger 107 will be brought back into engagement with the contact strip. The speed may then be increased to nearly fifty miles an hour without carrying the pointer off from the contact strip. The same is true of the action of this 110 mechanism where the pointer or finger 107 is coasting with the danger contact strip. If the train exceeds the speed limit of say, five miles an hour, the speed of the train must be reduced to at least one mile an hour in 115 order to bring the pointer back onto the danger contact strip. Thus upon a danger application of the brakes the speed will have to be reduced to one mile an hour, more or less, before it can be increased to five miles 120 an hour. I thus provide means for bringing the train upon the danger application of the brakes nearly to a full stop and then provide for an increase of speed to the maximum for a train running under a danger signal.

125 It is to be particularly noted that I provide means for securing some kind of a signal at the entrance of every block. If the system is not working properly or is 130

deranged then at the entrance of the block and upon the grounding of the test contact shoe, the lights will go out, the brakes will be applied and the lights will remain out 5 and the brakes applied until either a new signal is secured or the damage is repaired. If the track ahead is clear a clear signal will be received; if on the contrary there is a train on the block ahead, a cautionary 10 signal is received, and if there is a train on the same block a danger signal is received. A failure to receive a clear signal after the "test" will cause an application of the brakes which will bring the train 15 to a stop unless the engineer presses the circuit breaker 71^a on the wire 71.

If a cautionary signal is received the speed of the train will be reduced to say, twenty miles an hour and the train will 20 continue to run at or under this speed throughout the block and until the next signal is received at the end of the block. If the danger signal is received the speed of the train will be reduced to five miles 25 an hour and continue to run at this speed through the block. It is impossible for the engineer to control this automatic application 30 of the brakes. The mechanism, however, permits the engineer to run at a proper cautionary, or a proper danger speed if the cautionary or danger signal has been received. The mechanism does not interfere in any way with the operation of the air 35 brakes and the system may be used in conjunction with semaphore signals disposed beside the track, if desired.

By the terms "vehicle" and "train", as employed in the following claims, I intend to include any vehicle or any number of 40 connected vehicles adapted to operate upon track rails, such as a locomotive, a locomotive and its tender, or what is commonly known as a train including a locomotive, tender and one or more cars.

45 Having thus described the invention what is claimed as new is:—

1. In a cab signal system, a normally closed brake controlling circuit, a circuit breaker in said circuit, a normally closed 50 circuit adapted to be shorted by a grounded track contact controlling the circuit breaker, a plurality of electrically actuated signals, signal controlling circuits, a normally closed circuit breaker controlled by each of said 55 signal controlling circuits adapted to open upon the grounding of its respective circuit and each operable to open the brake circuit; and independent track controlled contacts for grounding the signal controlling 60 circuits.
  2. In a cab signal system, a plurality of electrically actuated signals connected each in a normally open signal circuit with a source of energy, a plurality of main circuits, a pair of stick relay magnets govern- 65
- ing the signal circuits, a plurality of stick relay magnets each disposed in one of the main circuits and governing the circuits through the signal governing relays, and track contact controlled means for controlling the passage of the current through the second-named relay magnets. 70
3. In a cab signal system, a plurality of electrically actuated signals connected each in a circuit with a source of electrical energy, a plurality of main circuits, a pair of stick relay magnets governing the signal circuits, a plurality of stick relay magnets each in one of the main circuits and governing the circuits through the signal governing 75 relay magnets, track contact controlled means for controlling the passage of current through the second-named relay magnets, an electrically operated brake controlling device, and means controlled by said pair of stick relay magnets for controlling the passage of current through the brake controlling device. 80
4. In a cab signal system, the combination with a brake controlling valve, and electrically actuated means for controlling said valve, of a generator, a clear signal, a cautionary signal and a danger signal, each disposed in a circuit with the generator, of means for electrically completing a circuit 90 through either the clear, cautionary or danger signals, the completion of the circuit through the clear signal acting to release the brakes, the completion of the circuit through the cautionary or danger signals 95 acting to apply the brakes, said means including a plurality of stick relays co-operating one with each of the signals and controlling the circuit of the brake actuating means, and means for manually releasing 100 the brakes after the automatic application thereof. 105
5. In a cab signal system of the character described, a brake controlling valve, means for urging said valve to open position, an electromagnet holding said valve closed, a generator in a normally closed circuit with said electromagnet, a circuit breaker arranged in said circuit, a magnet controlling the circuit breaker, a movable speed controlled member, a plurality of contact strips over which the speed controlled member moves and with which it has electrical engagement, said strips having different lengths, each of said strips being connected 110 in an independent circuit with the generator and through the speed controlled member and the last-named magnet to a ground, and means including track contacts for breaking the circuit through any of said strips 115 and completing the circuit through the other of said strips, whereby to render said last-named strip active, whereby when the speed controlled member moves beyond the extremity of such active strip due to the speed 120
- 125
- 130

of the vehicle, the circuit breaker magnet will be deenergized to thereby cause deenergization of the brake controlling magnet.

6. In a cab signal system, a pair of relays in normally closed circuits, clear and cautionary signal circuits controlled by both relays, a danger signal circuit controlled by one relay, test, clear, cautionary and danger circuits, and relays controlled by such circuits and in turn controlling the first relays and, consequently, the signals.

7. In a cab signal system, test, clear, cautionary and danger circuits, a relay controlled by each circuit, clear, cautionary and danger signal circuits, an appropriate signal device in each of the latter circuits, means controlled by the test circuit relay for rendering the clear and cautionary signal circuits inactive and the danger signal circuit active, means controlled by the clear circuit relay for rendering the clear signal circuit active and the cautionary and danger signal circuits inactive, means controlled by the cautionary circuit relay for rendering the cautionary signal circuit active and the clear and danger signal circuits inactive, and means controlled by the danger circuit relay for rendering the danger signal circuit active and the clear and cautionary signal circuits inactive.

8. In a cab signal system, a brake controlling circuit, a plurality of main track contact controlled circuits, brake circuit controlling circuit breakers, one controlled by each of the main circuits, a plurality of brake circuit controlling circuits, a multiple speed governed circuit breaker common to and independently controlling the latter circuits, and means for reclosing certain of the brake circuit controlling circuit breakers if opened to reclose the brake controlling circuit if it is not also opened by the speed governed circuit breaker.

9. In a cab signal system of the character described, a clear, a cautionary and a danger signal shoe, a source of electrical energy, each of said shoes being connected in an independent main circuit, with said source of energy, an electrically actuated brake controlling mechanism in a normally closed circuit with the source of energy, a plurality of electrically actuated signals corresponding in number to the shoes, a plurality of multi-point controlling relays disposed one in each main circuit, a plurality of multi-point relays controlling the brake circuit and normally energized to hold said circuit closed, the condition of the first-named relays controlling the condition of the second-named relays, and a plurality of multi-point relays in a normally closed circuit with the source of energy controlling the passage of current to the signals, the energizing of said last named relays being controlled by the first and second named sets of relays.

10. In a cab signal mechanism of the character described, a source of electrical energy, test, clear, cautionary and danger shoes each connected in an independent main circuit with said source of energy, a brake controlling valve, means for urging the valve to an open position, an electro-magnet urging the valve to a closed position, said electro-magnet being connected in a normally closed brake circuit with the source of energy, a plurality of circuit breakers in said circuit, controlling relay magnets disposed in the main circuits, the magnet disposed in the test circuit being a stick relay magnet, clear, cautionary and danger signals, a movable train speed governed element, a clear, cautionary and danger contact strips over which the said element moves and with which it has electrical engagement, said strips being of different lengths, stick relays controlling the passage of current from the source of energy to each of said clear, cautionary and danger signals and to each of said strips and rendering any two of said strips and corresponding signals inactive when the other one of said strips and said signals is rendered active, a circuit breaker arranged in the brake circuit, a magnet controlling said circuit breaker and connected in circuit through said speed governed element and said contact strips with the source of energy, additional relay magnets controlled by the first-named relay magnets controlling the passage of current through the signal controlling stick relays by controlling the grounding of the circuits through them, additional circuit breakers disposed in the brake circuit and controlled by the additional relay magnets and acting to break the circuit through the brake controlling magnet upon the passage of current either through the test, the cautionary or the danger circuits, and manually operable means for closing the circuit through the brake controlling circuit after it has been broken by the grounding of the test, caution or danger shoes and provided the movable speed governed element is in contact with the contact strip corresponding to the shoe which has been grounded.

11. In a cab signal system, a pair of relays in normally closed circuits, clear and cautionary signal circuits controlled by both relays, a danger signal circuit controlled by one relay, and track contact controlled test, clear, cautionary and danger circuits controlling the relays.

12. In a cab signal system, a pair of relays in normally closed circuits, clear and cautionary signal circuits controlled by both relays, a danger signal circuit controlled by one relay, additional relays controlling the first relays and, consequently, the signals, and track contact controlled test, clear, cau-

tionary and danger circuits controlling the additional relays.

13. In a cab signal system, test, clear, cautionary and danger circuits, a relay controlled by each circuit, clear, cautionary and danger signal circuits, an appropriate signal device in each of the latter circuits, and means controlled by the test, clear, cautionary and danger circuits whereby 10 when any signal is rendered active the other signals are rendered inactive.

14. In a block signal system, an electrical valve mechanism adapted when energized to be closed, a circuit normally energizing 15 such mechanism, an electrical circuit breaker in the circuit, a plurality of circuits common to and controlling the circuit breaker, means in each of the latter circuits for closing its circuit, and a plurality of 20 circuits for controlling such means, such latter circuits being so arranged that but one of them can be closed at any given time.

15. In a block signal system, the combination with a brake controlling mechanism, 25 of a track controlled clear signal, a track controlled caution signal, a danger signal controlled by a normally closed circuit adapted to be shorted by a grounded track contact, means for actuating the brake controlling 30 mechanism to apply the brake upon the receipt of a danger or caution signal, means for actuating the brake controlling mechanism to release the brake upon receipt of a clear signal, and means controlling the 35 speed of the vehicle under any signal.

16. In a block signal system, the combination with a vehicle, of a brake actuating mechanism, track controlling test, clear, caution and danger circuits, means for actuating 40 the brake actuating mechanism to apply the brake upon shorting of the test circuit unless another circuit proper to the condition of the block is subsequently grounded, means for actuating the brake actuating 45 mechanism to apply the brake upon grounding of the danger or the caution circuits, and means operable upon grounding of the clear circuit to actuate the brake actuating mechanism to prevent application of the 50 brake unless the speed of the vehicle is above the maximum speed for clear traffic.

17. In a cab signal system, a normally closed brake controlling circuit, a circuit breaker in said circuit, a multiple speed governed circuit breaker controlling the first 55 circuit breaker, a plurality of circuits common to the speed governed circuit breaker, a pair of relays controlling said latter circuits and so arranged that when any one 60 of the latter circuits are active the others are inactive, whereby by suitable operation of the relays the vehicle speed may be limited to any one of a predetermined number of speeds for which the speed governing circuit breaker is adapted.

18. In a cab signal system, a normally closed brake controlling circuit, a circuit breaker in said circuit, a multiple speed governed circuit breaker controlling the first 70 circuit breaker, a plurality of circuits common to the speed governed circuit breaker, a pair of relays controlling said latter circuits and so arranged that when any one of the latter circuits are active the others are inactive, whereby by suitable operation 75 of the relays the vehicle speed may be limited to any one of a predetermined number of speeds for which the speed governing circuit breaker is adapted, and track contact controlled means governing the operation of 80 the relays.

19. In a cab signal system, a normally closed brake controlling circuit, a circuit breaker in said circuit, a multiple speed governed circuit breaker controlling the first 85 circuit breaker, a plurality of circuits common to the speed governed circuit breaker, a pair of relays controlling said latter circuits and so arranged that when any one of the latter circuits are active the others 90 are inactive, whereby by suitable operation of the relays the vehicle speed may be limited to any one of a predetermined number of speeds for which the speed governing circuit breaker is adapted, and track contact 95 controlled means for independently opening the brake controlling circuit.

20. In a cab signal system, a normally closed brake controlling circuit, a circuit breaker in said circuit, a multiple speed 100 governed circuit breaker controlling the first circuit breaker, a plurality of circuits common to the speed governed circuit breaker, a pair of relays controlling said latter circuits and so arranged that when 105 any one of the latter circuits are active the others are inactive, whereby by suitable operation of the relays the vehicle speed may be limited to any one of a predetermined number of speeds for which the speed governed circuit breaker is adapted, and track contact controlled means for independently opening the brake controlling circuit, said means also controlling the relays.

21. In a cab signal system, a normally 115 closed brake controlling circuit, a plurality of circuit breakers in the circuit, a plurality of speed governing circuits, a speed governed circuit breaker common to all of the speed governing circuits and to one of the 120 first mentioned circuit breakers, a pair of relays controlling the speed governing circuits and so arranged that when one of such circuits is active the others are inactive, and track contact controlled means for opening 125 and closing the others of said first mentioned circuit breakers.

22. In a cab signal system, a normally closed brake controlling circuit, a plurality of circuit breakers in the circuit, a plurality 130

- of speed governing circuits, a speed governed circuit breaker common to all of the speed governing circuits and to one of the first mentioned circuit breakers, a pair of 5 relays controlling the speed governing circuits and so arranged that when one of such circuits is active the others are inactive, and track contact controlled means for opening and closing the others of said first mentioned 10 circuit breakers, said track contact means also controlling the relays to select which speed governing circuit shall be active.
23. In a cab signal system, a normally 15 closed brake controlling circuit, a plurality of circuit breakers in the circuit, a plurality of speed governing circuits, a speed governed circuit breaker common to all of the speed governing circuits and to one of the 20 first mentioned circuit breakers, a pair of relays controlling the speed governing circuits and so arranged that when one of such circuits is active the others are inactive, and track contact controlled means for opening 25 and closing the others of said first mentioned circuit breakers, said track contact means also controlling the relays to select which speed governing circuit shall be active, and manually operable means for closing 30 any circuit breaker opened by the track contact controlled means whereby the speed governing circuit selected by such means through its control of the first mentioned circuit breaker may control the speed of the 35 vehicle.
24. In a cab signal system, a normally closed brake controlling circuit, a plurality of circuit breakers in said circuit, a plurality of circuits controlling one of the 40 circuit breakers, a multiple speed governed circuit breaker arranged to open and close said latter circuits, a plurality of signal circuits, a pair of relays controlling the circuits controlling the first mentioned circuit breaker 45 and also controlling the signal circuits whereby when any one of the first mentioned circuits is rendered active its corresponding signal circuit is rendered active and the others of the first mentioned circuits 50 and the others of the signal circuits are rendered inactive.
25. In a cab signal system, a normally closed brake controlling circuit, a plurality of circuit breakers in said circuit, a plurality 55 of circuits controlling one of the circuit breakers, a multiple speed governed circuit breaker arranged to open and close said latter circuits, a plurality of signal circuits, a pair of relays controlling the circuits 60 controlling the first mentioned circuit breaker and also controlling the signal circuits whereby when any one of the first mentioned circuits is rendered active its corresponding signal circuit is rendered active 65 and the others of the first mentioned cir- cuits and the others of the signal circuits are rendered inactive, said relays being controlled by the others of the first mentioned circuit breakers.
26. In a cab signal system, a normally 70 closed brake controlling circuit, a plurality of circuit breakers in said circuit, a plurality of circuits controlling one of the circuit breakers, a multiple speed governed circuit breaker arranged to open and close 75 said latter circuits, a plurality of signal circuits, a pair of relays controlling the circuits controlling the first mentioned circuit breaker and also controlling the signal circuits whereby when any one of the first 80 mentioned circuits is rendered active its corresponding signal circuit is rendered active and the others of the first mentioned circuits and the others of the signal circuits are rendered inactive, said relays being controlled by the others of the first mentioned circuit breakers, and track contact controlled means for governing the operation of 85 said last named circuit breakers.
27. A cab signal system including a brake 90 controlling circuit, a circuit breaker therein, clear, cautionary and danger circuits controlling the circuit breaker, a speed governed circuit breaker common to said circuits, clear, cautionary and danger signal 95 circuits, a pair of coöperating relays, one of which independently controls the two danger circuits and both of which coöperatively control the remaining of the two groups of circuits, additional circuit breakers 100 operating to control the brake controlling circuit, one of them controlling one of the relays and the other the other of the relays, track contact controlled means governing the opening of said last mentioned circuit 105 breakers, and manually actuatable means for reclosing either of the last mentioned circuit breakers after it has been opened by the track contact controlled means.
28. A cab signal system including a brake 110 controlling circuit, a circuit breaker therein, clear, cautionary and danger circuits controlling the circuit breaker, a speed governed circuit breaker common to said circuits, clear, cautionary and danger signal circuits, a pair 115 of coöperating relays, one of which independently controls the two danger circuits and both of which coöperatively control the remaining of the two groups of circuits, additional circuit breakers operating to control the brake controlling circuit, one of them controlling one of the relays and the other the other of the relays, track contact controlled means governing the opening of said last mentioned circuit breakers, manually actuatable means for reclosing either of the last mentioned circuit breakers after it has been opened by the track contact controlled means, and additional track contact controlled means including whichever 120
- 125
- 130

- one of the clear, cautionary and danger circuits is active for opening the first mentioned circuit breaker.
29. A cab signal system including a brake controlling circuit, a circuit-breaker therein, clear, cautionary and danger circuits controlling the circuit breaker, a speed governed circuit breaker common to said circuits, clear, cautionary and danger signal circuits, 5 a pair of coöperating relays, one of which independently controls the two danger circuits and both of which coöperatively control the remaining of the two groups of circuits, additional circuit breakers operating 10 to control the brake controlling circuit, one of them controlling one of the relays and the other the other of the relays, track contact controlled means governing the opening of said last mentioned circuit breakers, 15 manually actuatable means for reclosing either of the last mentioned circuit breakers after it has been opened by the track contact controlled means, and additional track contact controlled means including whichever 20 one of the clear, cautionary and danger circuits is active for opening the first mentioned circuit breaker, the operation of any one of the first mentioned track contact controlled means subsequent to the operation 25 of the last mentioned additional track contact controlled means again rendering the clear, cautionary or danger circuits active.
30. In a block signal system, the combination with a vehicle, of a brake actuating mechanism, track controlled test, clear, caution and danger circuits, means for actuating the brake actuating mechanism to apply the brake upon shorting of the test circuit unless another circuit proper to the condition of the block is subsequently grounded, 35 means for actuating the brake actuating mechanism to apply the brake upon the grounding of the danger or the caution circuits, means operable upon grounding of the clear circuit to actuate the brake actuating mechanism to prevent application of the brake, independent manually operable means for actuating the brake actuating mechanism to release the brake after grounding of the danger or caution circuits, and means controlling the speed of the vehicle after grounding of the clear circuit, after manual release of the brake subsequent to grounding of the danger circuit and after manual release of the brake 40 subsequent to grounding of the caution circuit.

In testimony whereof I affix my signature in presence of two witnesses.

MARSENA R. JULIAN. [L.S.]
